UNITED STATES PATENT OFFICE.

WILLIAM HOPPER, OF JEFFERSON, IOWA.

WIRE-FENCE STRETCHER.

No. 895,862.

Specification of Letters Patent.

Patented Aug. 11, 1908.

Application filed January 20, 1908. Serial No. 411,639.

To all whom it may concern:

Be it known that I, WILLIAM HOPPER, a citizen of the United States, and a resident of Jefferson, in the county of Greene and State of Iowa, have invented a new and Improved Wire-Fence Stretcher, of which the following is a full, clear, and exact description.

This invention relates to certain improvements in devices for stretching wire fences while the wire is being secured to the fence post, and more particularly to that type of stretcher in which a clamping mechanism is employed in connection with clamping means, whereby the latter is prevented from becoming disengaged during the stretching action.

The invention consists in the provision of a lever, to one end of which the tension means is secured, and so disposed that the movement of the lever tends to tighten the clamping means.

Reference is to be had to the accompanying drawings, forming a part of this specification, in which similar characters of reference indicate corresponding parts in all the figures, and in which

Figure 1 is a perspective view of one embodiment of my invention; Fig. 2 is a top plan view of the mechanism for gripping the wire fencing; and Fig. 3 is a side elevation of a portion of the mechanism shown in Fig. 2.

The specific form of stretcher illustrated in the accompanying drawings involves in its construction a clamping or gripping mechanism adapted to engage with the fencing, and mechanism adapted for engagement with a fence post for applying tension to the fencing and bracing the post at the same time.

The clamping or gripping mechanism includes two clamping bars 10 and 11, each of slightly greater length than the height of the fencing and adapted to engage with opposite sides of the fencing to hold the latter between said clamping bars or members. The engaging surfaces of the two members are preferably so formed as to effectively bind the fencing in position. For instance, the bar 11 may be provided with a groove extending longitudinally thereof, and the bar 10 may be provided with a longitudinally-extending flange or projection 12 adapted to enter this recess or groove. Secured to the clamping bar 11 are a plurality of bracket arms 13, extending substantially parallel, and each bracket arm engages with the sur-

face of the bar 11 opposite to the groove and extends across one side of the bar and terminates in an eye or loop 14. The outer ends of the bracket arms are connected together by a vertically-disposed rod 15, which also serves as a pivot for a lever frame hereinafter described. The clamping bar 10 carries a plurality of lever arms 16, disposed adjacent the bracket arms 13, and each arm 16 is so formed that when the outer end thereof is adjacent the end of the corresponding bracket arm, the two clamping members will be pressed tightly together. Each lever arm 16 terminates at one side of the clamping bar 10 in a pin 17, adapted to extend through the eye 14 of the corresponding bracket arm 13.

Mounted on the rod 15, is a lever frame, including two vertically-disposed bars 18 and 19, connected together by a plurality of transverse bars 20, the central portion of each of which is pivoted on the rod 15. The means for applying tension to the fence preferably includes a chain 21, and this chain is connected to the bar 18 of the lever arm. The frame when moved to a position at substantially right angles to the bracket arms 13, as shown in dotted lines in Fig. 2, permits of a movement of the lever arms 16 and the removal of the clamping bar 10 from the clamping bar 11. After the wire fencing is brought into engagement with the clamping bar 11 and the clamping bar 10 is placed in position by inserting the pins 17 through the eyes 14, the lever arms 16 are moved to grip the fencing between the clamping bars and the lever frame is straightened to a position in substantial alinement with the bracket arms 13. The bar 19 of the frame then engages with the lower arm 16 and positively prevents the separation of the clamping bars while the tension is being applied to stretch the fencing. The means for applying this tension preferably includes two horizontally-disposed supports 22 and 23, each having one end thereof curved to adapt it to engage with a fence post 24, and having the opposite end thereof adapted to receive a vertically-disposed shaft 25, around which the chain 21 may be wound. The lower support 23, together with a transverse member 26, form a base for supporting the lower end of the shaft, and also for retaining the tension-applying means in an upright position. The upper support 22 is preferably provided with a bracket 27 hinged thereto and adapted to engage with the lower sup-

port 23 for holding the upper one at the desired elevation adjacent the post, and also has pivoted thereto two iron braces 28, the lower ends of which are adapted for insertion 5 in suitable eyelets at the outer ends of the base member 26. For rotating the shaft 25, a suitable hinge member 29 is secured to the upper end thereof, said hinge member having suitable handles 30 extending therefrom in 10 opposite directions.

For bracing the post during the stretching action, I provide a suitable detachable brace, including a diagonal bar 31, having its upper end adapted to engage with the post adjacent 15 the top thereof and having its lower end adapted to engage with a cleat 32 on a base-board 33 spaced a short distance from the post. In applying the bracing means, the base 33 is placed in position at a short distance 20 from the post and the brace bar 31 placed with one end against the cleat 32 and the other end against the post. A rope, chain or cable 34 is secured to one end of the cleat 32 and is then passed around the base 25 of the post and secured to the opposite end of the cleat. The brace 31 is then placed against the cleat and the post, and pressed down until the cable is as taut as possible.

It is thought the operation of the device 30 will be sufficiently evident from the above description, but in brief, it may be stated that the tension-applying means is assembled and placed in position as illustrated in Fig. 1, and adjacent the post in advance of 35 the one to which it is desired to fasten the fencing. The post unless it be provided with terminal bracing, is braced by the diagonal bracing illustrated and the clamp secured to the fencing. Upon the rotation of the shaft, 40 the fencing may be drawn as tightly as desired and firmly secured to the post preceding the one to which the tension is applied. The clamp is then unfastened and secured to the fencing at a point farther along the 45 length thereof, and the tension-applying means removed to the next succeeding post. Preferably, two sets of the diagonal bracing

means for the post are provided, one of these being in operation at all times and bracing the post against which the greatest lateral 50 strain is exerted. This is obviously the post having the tension-applying means in engagement therewith during the stretching action and the last post to which the fencing is secured during the time the apparatus is 55 being shifted to the next post.

Having thus described my invention, I claim as new and desire to secure by Letters Patent:

1. A fence-stretcher, comprising a tension- 60 applying means adapted to engage with a fence post, a clamping means adapted to engage with the fencing, and flexible connections between said tension-applying means and said clamping means, said clamping 65 means comprising two clamping members adapted to engage with opposite sides of the fencing to hold the latter therebetween, a bracket arm carried by one of said clamping members, a lever arm carried by the other of 70 said members, and means for connecting said flexible connections and said clamping means, including a member pivoted to said bracket arm and in engagement with said lever arm for holding the clamping members in engagement 75 during the stretching action.

2. A fence-stretcher, including two clamping members adapted to engage with opposite sides of the fencing, a bracket arm carried by one of said members, a lever arm carried by the other of said members, and a lever pivoted to said bracket arm and in engagement with said lever arm, and means in engagement with said lever for applying tension to the fencing and locking the clamping 85 members in engagement with each other.

In testimony whereof I have signed my name to this specification in the presence of two subscribing witnesses.

WILLIAM HOPPER.
